ATTYS.

UNITED STATES PATENT OFFICE.

PAUL E. JOHNSON, OF CHICAGO, ILLINOIS.

THERAPEUTIC LAMP.

1,403,119.

Specification of Letters Patent. Patented Jan. 10, 1922.

Application filed June 9, 1920. Serial No. 387,623.

To all whom it may concern:

Be it known that I, PAUL E. JOHNSON, a citizen of the United States, residing at Chicago, in the county of Cook and State of Illinois, have invented a certain new and useful Improvement in Therapeutic Lamps, of which the following is a specification.

My invention relates to therapeutic lamps, and the object of the invention is to provide an apparatus which will render available to the operator rays having a full range of wave lengths. It is well known to those experienced in the treatment of pathological conditions, congestion and other physical disturbances by the aid of light and heat rays that rays of different wave lengths produce different physiological and therapeutic effects. My purpose is to render it possible for the operator to readily obtain the different wave lengths or any desired combinations of wave lengths required under any given conditions.

I accomplish my objects by the mechanism illustrated in the accompanying drawing in which—

Figure 1 is a side elevation, partly in section, of the chief portions of the apparatus as they appear when assembled.

Figure 2 is a plan section on the line 2—2, Figure 1.

Figure 3 is an elevation partly in section showing the quartz light or "burner," the view being taken from the plane indicated by the line 3—3, Figure 1.

Figure 4 is a sectional view on the line 4—4, Figure 1.

Figure 5 is a fragmentary bottom view of the rod which supports the quartz light.

Like numerals denote like parts throughout the several views.

According to the design selected to illustrate the invention, the lamp proper is supported from a sleeve 1 which is guided vertically upon a standard 2 by anti-friction rollers 3. In order that the sleeve may move freely and with little effort on the part of the operator, it is desirable to counterbalance it by means of a weight (not shown) which travels within the standard and is attached to a cord 4 which passes over a guide pulley 6 at the top of the standard. A set screw 7 is provided for securing the sleeve at any elevation desired.

The sleeve has a cross guide 8 for a rod 10 which supports the reflector housing 12 for the lamps. The rod may be moved hori-

zontally in the guide by means of a handle 13 of any suitable type and is prevented from rotating by means of a spline 14 which fits partially within the guide and partially within a groove 15 formed in the bottom of the guide. The lamp housing may thus be adjusted both horizontally and vertically.

The housing has a dome-like portion 16 terminating at the bottom in a cylindrical flange 18. At the top of the dome is a lamp socket 19 for the upper lamp 20. This is an ordinary screw socket provided with the usual terminals (not shown) and controlled by a switch 22. The lamp terminals are energized through a lamp cord or cable 24 of any suitable type. The lamp 20 is an incandescent electric lamp of desired wattage, usually from 500 to 1000. It emits rays having the longer wave lengths.

Mounted in the cylindrical flange portion of the housing is a tubular guide 26 for a rod 27. At the outer end this rod has a handle 28 of any suitable design and at the inner end carries a bracket 30 which extends at right angles to the rod and forms a support for a mercury vapor quartz lamp 32. The rod is longitudinally slideable in its guide and is normally prevented from rotating about its axis by means of a screw pin 34 mounted in 85 guide 26 and projecting into the slot 36 formed in the under side of the rod, as best shown in Figures 1, 4, and 5. At its outer end the slot has a transverse bend 38 which permits the rod to rotate slightly for starting the lamp, as will be hereinafter explained.

As the slot terminates at this bend it forms, in cooperation with the pin 34, a stop for limiting the inward movement of the rod. The parts are so proportioned that when the 95 rod has been pushed in as far as it will go, the lamp 32 will be substantially in line with the longitudinal axis of the upper lamp 20.

The quartz lamp or "burner" 32, previously 100 mentioned, is an article well known in the electrical industry and need not be described further than to say that it is, in the main, of tubular form, having a pocket 40 at one end for containing the mercury 41, except during the starting period. It has two terminals 42 energized by flexible conductors 44 leading from binding posts 46 mounted at a convenient point on the housing, as best shown in Figures 1 and 2. Electric energy 110 is supplied to the conductors 44 by suitable conductors 48, controlled by a switch 49 in-

dicated in dotted lines in Figure 1. The connections from the binding posts to the switch are not completely shown as they are of ordinary design and the drawing is more readily understood without them. As known by those familiar with these quartz lamps or mercury vapor lamps, such lamps emit rays of shorter wave length frequently known as "actinic" rays. To start the lamp burning, 10 the current is first turned on, then the lamp is tilted by rotating the rod 27. In this design the tilting action can occur only when the rod is pushed in to the limit, with the bend 38 opposite to the pin 34. The tilting 15 is for the purpose of completing the electric circuit through the mercury, after which the current is carried through the mercury vapor and the lamp is permitted to tilt back, under the action of gravity. The liquid 20 mercury then recollects in the pocket 40. The lamp is overbalanced for the purpose—the rod being located off center, away from the pocket 40.

In practice, when the operator is ready to 25 give a treatment he first positions the patient, then adjusts the apparatus vertically by moving the sleeve 1 upon the standard and sliding the rod 10 horizontally to the best position. He then decides what character 30 of emanations he desires. It is my understanding that the long rays emanating from the upper lamp 20 give in greater abundance heat rays whose chief function is for immediate relief of congestion or 35 pain; and that the short rays emanating from the quartz lamp 32 give in greater abundance "actinic" rays which are of value for destroying germs, arresting malignant growths, etc. The rays of longer wave length 40 penetrate more deeply while those of shorter length, emanating from the upper lamp, affect primarily the surface or portions of tissue near the surface. In some cases, however, it is desirable to employ both kinds of 45 rays simultaneously. My apparatus affords opportunity for using the different kinds of rays either one at a time or simultaneously. If both types of rays are wanted the operator adjusts the parts to the position shown 50 in full lines in Figure 1 and turns on both switches 22 and 49. He thus obtains a combination of rays having wave lengths ranging from the lowest to the highest within the compass of the two lighting units. If 55 the short rays are wanted alone, the operator turns off the switch 22 controlling the upper lamp and starts the lower lamp 32. As the lamp giving these rays of shorter wave length is the lower of the two lamps, 60 the upper one, naturally, cannot obstruct the rays. If it is desired to employ the rays of longer wave length, the switch 22 is turned on, the switch 49 turned off, and the lower lamp 32 retracted to the dotted line 65 position, Figure 1, by sliding the rod 27

outward in its bearing 26. Thus there will be nothing to obstruct the rays emanating from the upper lamp. It will thus be evident that the operator is afforded a choice which he can exercise with very slight effort. It is not necessary to change the position of the reflector or housing 16, 18 nor to take out or insert either type of lamp. Both types are instantly available and yet neither will obstruct the rays of the other 70 when used singly. When used simultaneously the slight obstruction offered by the lower lamp will be quite negligible, especially as it will be understood that ordinarily the two lamps will give off certain 75 quantities of rays which are similar or approximately so. By the use of this apparatus the operator may exercise his judgment and may, without interruption, substitute one type of ray for another at 80 any point in the treatment, or produce such combination as he may consider desirable.

Having thus described my invention, what I claim as new and desire to secure by Letters Patent is:

1. A therapeutic lamp having a concave reflector with a longitudinal axis, an incandescent lamp mounted within the housing, with the filament approximately at the axis thereof, and a mercury vapor 95 lamp adapted to also occupy a position at the axis of the housing, said mercury vapor lamp being movably mounted whereby it may be lighted without demounting it.

2. Apparatus of the class described having 100 a concave reflector provided with an incandescent lamp and a mercury vapor lamp, the two lamps being adapted to lie approximately at the axis of the reflector and the incandescent lamp being located farther 105 within the reflector than the mercury vapor lamp, the mercury vapor lamp being tilt-able to enable it to be lighted and also movable to permit it to be withdrawn from the field of the incandescent lamp.

3. In a device of the class described, the combination of a housing in the form of a dome-like reflector, a lamp socket carried in the top of the reflector, an upper lamp adapted to fit into the socket, a slide 115 rod, a bearing for said slide rod carried by the reflector near the mouth thereof and extending radially, and a mercury vapor lamp mounted at the inner end of the rod, said vapor lamp having a mercury tube 120 lying approximately in a plane at right angles to the rod, the rod being rotatable in its bearing for tilting the tube for starting the lamp.

4. In a device of the class described, the combination of a dome-like reflector, an incandescent lamp having a filament located approximately at the axis of the reflector, a mercury vapor lamp, a stationary pin, and a slide rod for carrying the vapor 130

- lamp, the rod being slidably mounted at the mouth of the reflector, and having a longitudinal slot adapted to receive the end of the pin, the slot having a transverse bend at one point whereby the rod may be rotated when in one position, for tilting the vapor lamp, and is otherwise non-rotatable.
5. In a device of the class described the combination of a dome-like, approximately 10 parabolic reflector having an incandescent lamp mounted in fixed position within the reflector with the filament approximately at the axis of the reflector, and a mercury vapor tube lamp arranged approximately at the axis of the reflector but having its 15 length approximately transverse to the axis of the reflector, the tube lamp being located nearer the mouth of the reflector, and means for supporting the tube lamp movably without detaching it, said means being 20 adapted to permit the tube lamp to tilt to enable it to be lighted.
- In witness whereof, I have hereunto subscribed my name.

PAUL E. JOHNSON.
